(57) **CLAIM**

The ornamental design for a product display fixture, as shown and described.

DESCRIPTION

FIG. 1 is a top and front perspective view of a product display fixture showing our new design;

FIG. 2 is a top and rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof wherein the non-shaded bottom surface forms no part of the claim.

In the drawings, the evenly-spaced broken lines depict portions of the article that form no part of the claimed design; the dash-dot-dash lines represent the boundary of the claimed design and form no part thereof.
